UNITED STATES PATENT OFFICE.

CHARLES E. STEWART, OF SAN FRANCISCO, CALIFORNIA.

BOAT-RELEASING APPARATUS.

No. 924,201.

Specification of Letters Patent.

Patented June 8, 1909.

Application filed November 7, 1908. Serial No. 461,495.

To all whom it may concern:

Be it known that I, CHARLES E. STEWART, a citizen of the United States, residing in the city and county of San Francisco and State 5 of California, have invented certain new and useful Improvements in Boat-Releasing Apparatus, of which the following is a specification.

My invention relates to that class of apparatus in connection with ships' boats, which has for its object the release of the boat from its lashings, preparatory to lowering it from the davits.

In practice, the boat when hoisted by the 15 tackles to the davit-heads, is supported and held in place by hangers and grips, the former taking the weight off the tackles, and the latter holding the boat snugly in against a spar lashed between the davits. When 20 these hangers and grips are released, the boat swings out to position ready to be lowered by the tackles. It is the common practice to secure the inner ends of the hangers and grips, to the davits, by means of tackles 25 which have to be separately released and let go, in order to free said ends, thus taking up valuable time which in an emergency may be of the highest importance. This operation also lacks in precision of simultaneous action, 30 which in the case of four ends to be released is a decided disadvantage and may result in disaster in lowering away the boat.

The object of my invention is to remedy these difficulties by providing for the precise 35 and simultaneous release, by a single operation, of the inner ends of both hangers and both grips, so that the boat may be instantly released to swing out to position to be lowered.

To this end, my invention consists in the 40 novel construction and arrangement of the apparatus, which I shall now fully describe, by reference to the accompanying drawings in which—

Figure 1 is a perspective view showing the boat at the davit-heads and lashed in place by the hangers and grips, the inner ends of which are detachably secured to the davits by means of hooks, which are adapted by a 45 single operation to be simultaneously tripped. Fig. 2 is a perspective view, enlarged, of one of the trip-hooks.

1 indicates an awning rail, and 2 are the davits.

3 is a spar which is lashed between the davits, and is provided with buffers 4.

5 is the boat.

6 are the hoisting and lowering tackles, which are connected with the boat fore and aft and with the davit-heads in some usual manner. I have, for the sake of clearness, shown the falls of these tackles broken away, it being readily understood that they will lead, as usual, to some belaying cleat or cleats. These tackles form no part of my invention 65 and need no further illustration.

7 are the hangers, one fore and one aft. These are secured at their outer ends to the davit-heads, and they thence pass under the boat, and at their inner ends are also secured 70 to the davits, by the tripping means which I shall presently describe.

8 are the grips. There are two of these. One of them is secured at its outer end to the head of one davit, and it thence passes diagonally outside of and against and under the boat to the other davit, to the body of which it is secured by the tripping means to be presently described. The other grip is similarly but reversely arranged with respect to 80 the two davits, as is clearly shown. It will now be seen that the hangers 7 take the weight of the boat, while the grips 8 hold it snugly in against the buffers 4 of the spar 3.

Referring now to Fig. 2, I show a trip-hook 85 indicated as a whole by 9. It comprises an open or slotted body portion 10, a trip-arm 11 hinged to the body portion and a slip-link 12, adapted to slide upon both the body portion and the trip-arm, whereby it both holds 90 and releases said trip arm. Referring again to Fig. 1, it will be seen that I use four of these trip-hooks 9. Each is suitably lashed to a davit. One receives upon its trip-arm, the ringed-end of one hanger; a second similarly receives the end of the other hanger; a third receives the end of one grip and a fourth receives the end of the other grip.

13 are two lines, the falls of which are belayed upon a convenient cleat 14 on a stanchion 15 of the awning rail 1. These lines pass upwardly and diverge over a small block 16. Each is then branched into two lines as shown, one branch of each passing under a small block 17, one on each davit, 100 and thence up to and over a block 18 on each davit and thence to the slip link 12 of the hooks 9, which secure the inner ends of the hangers 7; and the ends of these branches are secured to the eyes of said slip-links. 105 The other branches pass over the blocks 17 down to and under blocks 19 and thence to 110

the slip links of the hooks 9 which secure the inner ends of the grips, and are secured to the eyes of said links. It will now be seen that upon pulling upon the lines 13, the slip-links 12 of all four hooks 9 will be simultaneously pulled off the trip arms 11, which, swinging out under the strain, will allow the ringed-ends of both hangers and both grips to slip off the trip arms; and thus all four lashings will swing clear and hang free from their outer ends. The boat is thus released and will swing out ready for lowering.

Having thus described my invention what I claim as new and desire to secure by Letters Patent is:—

1. A boat-releasing apparatus comprising a pair of hangers supporting the boat from the davit-heads, a pair of grips to hold the boat in when at said heads, means for detachably securing the inner ends of said hangers and grips to the davits, and means for simultaneously releasing said inner ends from their securing means.

2. In a boat-releasing apparatus, and in combination with a pair of davits, a pair of hangers secured at their outer ends to the davit-heads, and thence passing under the boat fore and aft, a pair of grips secured at their outer ends to the davit heads, and thence passing under the boat, means for detachably securing the inner ends of the hangers and grips to the davits, and means for simultaneously releasing said inner ends from their securing means.

3. A boat-releasing apparatus comprising a pair of hangers supporting the boat from the davit-heads, a pair of grips to hold the boat in when at said davit-heads, trip-hooks securing the inner ends of said hangers and grips to the davits, and means for simultaneously tripping all of said hooks.

4. In a boat-releasing apparatus, and in combination with a pair of davits, a pair of hangers secured at their outer ends to the davit-heads, and thence passing under the

boat fore and aft, a pair of grips secured at their outer ends to the davit heads and thence passing under the boat, trip-hooks securing the inner ends of the said hangers and grips to the davits, and means for simultaneously tripping all of said hooks.

5. A boat-releasing apparatus comprising a pair of hangers supporting the boat from the davit-heads, a pair of grips to hold the boat in when at said davit heads, trip-hooks secured to the davits and consisting of a body portion, a trip-arm hinged thereto, and detachably engaging the inner ends of the hangers and grips, and a slip-link on the body portion adapted to engage and release the trip arm, and trip-lines connected with the slip-link of each trip-hook for simultaneously operating all said links to release the trip-arms and detach the inner ends of both hangers and both grips.

6. In a boat-releasing apparatus, and in combination with a pair of davits, a pair of hangers secured at their outer ends to the davit-heads, and thence passing under the boat fore and aft, a pair of grips secured at their outer ends to the davit heads and thence passing under the boat, trip-hooks secured to the davits and consisting of a body portion, a trip-arm hinged thereto, and detachably engaging the inner ends of the hangers and grips, and a slip-link on the body portion adapted to engage and release the trip arm, and trip-lines connected with the slip-link of each trip-hook for simultaneously operating all said links to release the trip-arms and detach the inner ends of both hangers and both grips.

In testimony whereof I have signed my name to this specification in the presence of two subscribing witnesses.

CHARLES E. STEWART.
